MEANS FOR RELIEVING PRESSURE ON
TOP ROLLS

James C. Stubbs, Rockingham, N. C.

Application November 10, 1933, Serial No. 697,465

1 Claim. (Cl. 19—136)

This invention relates to means for relieving the pressure on the top rolls of spinning frames, drawing frames, slubbers, intermediates, and in fact all types of machinery for preparation of 5 yarn in strand form in which the sliver or strand is passed through a series of drawing rolls.

Heretofore, attempts have been made to provide such a mechanism, but on account of the fact that the prevailing type of frame has a broad 10 roll stand supporting board or member, there is only a very small space left between the pressure levers and the roll stand supporting board, thus rendering the placing of a rod with cams thereon impracticable. I have solved the difficulty by 15 placing between the roll stand supporting member and the levers a flat elongated member which lies flat on the top surface of the roll stand support when not in use and which is pivoted along one edge thereof, so that when it occupies a substantially 20 vertical position it elevates the levers and relieves the pressure from the top rolls.

It is well known, that on account of the fact that the bottom rolls are of steel and have bosses thereon which are fluted, and as the top rolls are 25 leather covered, cork covered and the like, that when the machines remain idle for an appreciable length of time, the leather or cork top rolls will have flat places or furrows impressed therein which damages the rolls and causes them to be 30 relegated to the repair shop for recovering.

It is an object of this invention to provide one or more flat bars between the levers and the roll stand board, with a lever thereon for operating the same, which lever acts as a stop for the bars 35 when they have passed dead center and holds them in elevated position.

Some of the objects of the invention having 40 been stated, details of the same will appear more fully when taken in connection with the detailed description hereinafter following, when read in view of the accompanying drawings, in which—

Figure 1 is a rear elevation of a drawing frame and the like showing my invention applied thereto;

Figure 2 is a vertical sectional view taken along the line 2—2 in Figure 1;

Figure 3 is a vertical sectional view taken along the line 3—3 in Figure 1.

Referring more specifically to the drawings the 50 numeral 10 indicates the roll stand supporting beam having mounted thereon a plurality of roll stands 11, the roll stands supporting a plurality of steel rolls 12 and a plurality of top rolls 13 which are usually covered with a composition 55 such as leather, cork and the like and adapted

to rest on the rolls 12 when the yarn is passed therebetween for drawing purposes. These top rolls are supported for rotation in members 14 pivoted on rod 15 and saddles 16 and 17 apply pressure to the top rolls, the pressure being derived through a stirrup 18, a lever 19 engaging a lever hook 20 at one end and a link 21 being adjustably mounted on the other and penetrating the roll stand supporting rail 10 and having a weight 22 on the lower end thereof, though in some instances a spring is used instead of a weight.

In any event there is a constant downward pressure exerted on the top rolls 13 by means of the weight 22 or a spring if the spring is used instead of a weight. This means that when the machinery is standing idle, that the portions of the top rolls pressing against the bottom rolls will become flattened or scarred on account of remaining in this one place for an appreciable 20 length of time and it is an object of this invention to provide means whereby this pressure can be released when the machine is not in operation.

On account of the small amount of space which appears between the levers 19 and the roll stand supporting beam 10 it is evident that a rod with cams thereon could not be used on account of lack of space. I therefore provide, usually two elongated flattened bars 25 and 26 which have holes bored therethrough along one edge 30 thereof which are penetrated by U-bolts 27, which pivotally mount these bars 25 and 26 at one edge thereof. I also secure to each of the bars 25 and 26 an arm or lever 28 or 29, not only for manipulating the bars 25 and 26 but also for holding these bars in adjusted position, as it is evident that when the bars are raised to their operative position, as shown in the left hand portion of Figure 1 and in Figure 2, that these levers 28 or 29 serve to limit the counter clock-wise movement of the bars as shown in Figure 2 and holds the bars in elevated position because they have passed their dead center and therefore these levers 28 and 29, not only serve the purpose of operating the flat bars 25 and 26, but also hold them 45 in elevated position.

Another advantage of this arrangement is that when the bars 25 and 26 are not in operative position they lie flat on the top surface of the roll stand supporting rail 10 and are therefore not in 50 position to catch lint and are also out of the way in case a brush or any other cleaning instrument is desired to be used. Furthermore, in mechanical cleaners which are traversed above the machinery, it is seen that these bars lying flat offer 55

no resistance to the air drafts which are directed downwardly onto the machinery while they are in the inoperative position.

This inoperative position is shown in the right hand portion of Figure 1 and in Figure 3, and when the machines are stopped over-night, or for an appreciable length of time, the operator moves the levers 28 and 29 to the position shown in the left hand portion of Figure 1 and in Figure 2, and thus the pressure on the top rolls is removed, and the life of the top rolls is greatly extended.

In the drawings and specification there has been set forth a preferred embodiment of the invention and although specific terms are employed, they are used in a generic and descriptive sense only, and not for purposes of limitation, the scope of the invention being set forth in the appended

20 claim.

I claim:

In fiber preparation machinery having a roll stand supporting board and top rolls and levers for applying pressure to the top rolls, a flat bar extending beneath a plurality of said levers and disposed between the roll stand supporting board and the levers and normally out of contact with the levers and occupying a plane parallel to the upper surface of the roll stand supporting board, means pivotally connecting one edge of the flat bar to the roll stand supporting board, an arm secured near the upper edge of the flat bar and normally occupying a vertical plane when pressure is applied to the roll, the free end of the arm engaging the top surface of the roll stand supporting board when the flat bar is moved on its pivot past its dead center to elevate the levers, the pressure on the levers holding the end of the arm against the roll stand supporting board.

JAMES C. STUBBS.
